United States Patent Office

Des. 176,239

Patented Nov. 29, 1955

176,239

DISPLAY FIGURE OR SIMILAR ARTICLE

Albert Werner, New York, N. Y.

Application February 8, 1955, Serial No. 34,422

Term of patent 3½ years

(Cl. D80—8)

Fig. 1

Fig. 2

Fig. 1 is a front perspective view of a display figure or similar article showing my new design; and Fig. 2 is a rear perspective view thereof.

I claim:

The ornamental design for a display figure or similar article, substantially as shown.
